US0D1017682S

(12) **United States Design Patent** (10) **Patent No.:** **US D1,017,682 S**
(45) **Date of Patent:** **** Mar. 12, 2024**

(54) **EYEGLASSES**

(71) Applicant: **Oakley, Inc.**, Foothill Ranch, CA (US)

(72) Inventors: **George Yoo**, North Hollywood, CA (US); **Nicolas Adolfo Garfias**, Long Beach, CA (US)

(73) Assignee: **Oakley, Inc.**, Foothill Ranch, CA (US)

(**) Term: **15 Years**

(21) Appl. No.: **29/792,944**

(22) Filed: **May 2, 2022**

(51) LOC (14) Cl. **16-06**

(52) U.S. Cl. **D16/326**

(58) **Field of Classification Search**

USPC D16/300, 306, 314, 315, 325; D22/199; D24/110.1, 110.2, 110.3; D29/102, 104, D29/105, 109
CPC . G02C 1/06; G02C 5/146; G02C 5/02; G02C 5/008

(57) **CLAIM**

The ornamental design for eyeglasses, as shown and described.

DESCRIPTION

FIG. 1 is a top front perspective view of eyeglasses showing the claimed design;

FIG. 2 is a front elevation view thereof;

FIG. 3 is a rear elevation view thereof;

FIG. 4 is a right side elevation view thereof, the left side elevation view being a mirror image thereof;

FIG. 5 is a top plan view thereof; and,

FIG. 6 is a bottom plan view thereof.

The broken lines in the figures show portions of the eyeglasses that form no part of the claimed design.

1 Claim, 6 Drawing Sheets
